DRINKING FOUNTAIN FOR FOWLS

Hugo Schölander, Jarpas, Sweden

Application January 6, 1936, Serial No. 57,811
In Sweden April 4, 1935

3 Claims. (Cl. 119—72)

The present invention relates to drinking fountains for fowls and has for its object the provision of a fountain constructed so as to prevent the splash and spilling of water when the fowl drinks.

As is well known, a hen or other fowl swallows only a portion of the quantity of water that it has taken into its bill and the cavity of its mouth. About twenty per cent of the whole quantity of water taken may normally by a rapid movement of the head be splashed in all directions. Such water dirties the surroundings of the fountain, wets the litter on the floor and necessitates a frequent change of the litter. It should be observed that the litter has to be changed as soon as it has become moist. Such change disturbs the fowls and causes decrease of the laying. Besides, wooden walls and floors in the proximity of the drinking fountain, which are exposed to splash of water, will be liable to rot.

In the use of a drinking fountain according to this invention, as above mentioned, all splash and spilling of water, when fowls drink, will be obviated.

In the drawing, wherein like characters of reference designate corresponding parts throughout.

Fig. 1 is a cross sectional side view of the invention taken on line I—I of Fig. 2.

Fig. 2 is a front elevation of the drinking fountain.

Fig. 3 is a cross sectional side view of a modification of the invention taken on line III—III of Fig. 4.

Fig. 4 is a front elevation of the modification shown in Fig. 3.

In Figs. 1 and 2 of the drawing, 1 is a drinking trough consisting of a bucket or the like in horizontal position with the upper portion 2a of the front wall or lid bent inwards so as to leave an opening between said portion and the lower portion 2 of the front wall or lid. Water has been poured into the drinking trough to the horizontal edge of the wall portion 2. 3 denotes a hood-shaped splash-guard provided in front of the wall portion 2a of the drinking trough and above the water line. The front wall 5 of the splash guard 3 inclines downward from the drinking trough and leaves an opening between its lower edge and the wall portion 2 of the drinking trough so that, for instance, a hen, shown in Fig. 1 with dotted lines, when standing upon the foot-rest 4 beneath and in front of the front edge of the drinking trough, can insert

her head and neck in the opening of the splash guard. In this position, the water will be within reach of the hen's bill. The splash guard 3 acts in essential degree by its front wall 5, projecting beyond the fowl's head, impeding the splash movement of the fowl. (As well known, the fowl when drinking directs its bill somewhat upwards.) Said wall or portion of the splash guard will also prevent the fowl from moving its head outside the splash guard before swallowing the water. Furthermore, the fowl will be prevented from moving its head so far backwards that spilt water dropping, for instance, from the chin-flaps of the hen falls outside the catch trough 6 for such spilt water suspended on the outside of the front wall 2 of the drinking trough 1. The opening of the splash guard is surrounded by channels 7, 8 by preference formed by the material of the splash guard at the inner side of the lower front and lateral edges thereof. If splashing occurs in spite of the splash impeding action of the splash guard 3 the water drops will be caught by the inner sides of the hood-shaped guard, and these drops will flow down and be collected by the channels 7, 8 conducting the water back to the drinking trough 1 or to the catch trough 6 for spilt water. Said catch trough 6 is placed as shown by Figs. 1 and 2 under the upper front edge of the drinking trough 1 and close to the front side thereof.

In Figs. 3 and 4, the drinking trough 10 has a channel-shape, and the hood-shaped splash guard 11 with inclined front wall 12 has been formed so as to suit the elongated form of the trough 10. Also, this splash guard is provided with channels 7, 8 at the lower edges adapted to conduct water splashed on the inside of the hood 11 back to the trough 10.

The drinking trough may be equipped with conduits for flowing water as shown at 9 in Figs. 3 and 4, or the trough may be filled according to the consumption of the water, as is the case in Figs. 1 and 2.

I do not desire to limit my invention to the embodiments above described but desire to be free to vary the details thereof without departing from the spirit of my invention.

What I claim is:—

1. In a drinking fountain for fowls, a drinking trough, a hood-like splash guard provided above and in front of the drinking trough, and said hood-like splash guard having such a shape as to extend down behind the head of the drink-

ing fowl in the position that it assumes when swallowing water taken into its bill.

2. In a drinking fountain for fowls, a trough, a hood-like splash guard in front of the drinking trough, and said hood-like splash guard having a front wall inclining downward from the trough so as to extend behind the head of the drinking fowl in the position that it assumes when swallowing the water taken into its bill.

3. In a drinking fountain for fowls, a trough, a splash guard provided above the trough, and channels at the lower edges of the splash guard and at the inside thereof adapted to conduct water splashed on the inside of the guard to the trough. 5

HUGO SCHÖLANDER.
